UNITED STATES PATENT OFFICE.

EDWIN ODELL, OF CENTRAL CITY, NEBRASKA.

OBSTETRICAL INSTRUMENT.

Application filed February 3, 1928. Serial No. 251,676.

My invention relates to obstetrical devices and more particularly to improvements in my prior Patent 1,614,679, January 18, 1927.

With the device disclosed in the above identified patent, it is necessary to exert strain upon the gripping tapes with one hand while the separable handle members are held in the other hand. It is therefore an object of this invention to provide an obstetrical device which, after being adjusted to the infant's head, may be manipulated with one hand to draw the infant from its mother.

Further the invention provides an obstetrical device embodying a pair of separable handle members and a flexible loop which is adjustable relative to the handle members so as to be correctly positioned about the object and subsequently maintained under tension incident to the outward pull on the handle members.

The invention also provides an obstetrical instrument having a slidable finger engaging element to which the ends of the loop are attached so that the loop may be tensioned about the object and maintained in this condition by sliding the finger engaging element relative to the handle members.

With the preceding and other objects and advantages in mind, the invention consists in the novel combination of elements, constructions and arrangement of parts to be hereinafter specifically referred to, claimed and illustrated in the accompanying drawings, wherein:

35 Figure 1 is a perspective of the invention in operative position;

Figure 2 is a top plan view with the head embracing loop removed;

Figure 3 is a perspective of one of the handle members being placed in operative position;

Figure 4 is a transverse section taken on line 4-4 of Figure 2;

Figure 5 is a similar view taken on line 45 5-5 of Figure 1; and

Figure 6 is a fragmentary perspective of a modification of the invention.

Referring to the invention in detail a pair of separable parallel handle members 5 and 6, having oppositely curved arms 7 formed at one end and terminating in eyes 8, is provided. When in operative position the handle members are arranged with the arms 7 in opposed relation and the eyes in transverse alinement. 50 In practice the handle members will be con-

structed from metal having a slight resiliency so that the arms can yield laterally.

At its opposite end one of the handle members carries a knob or spherical element 9 adapted to be engaged by the palm of the operator's hand during the extraction or pulling operation. A rectangular opening 10 is provided in the inner face of the spherical element 9 for the reception of the adjacent end of the handle member 6, as illustrated in Figure 2.

In order to grip the infant's head, a flexible adjustable loop 11 is provided and cooperates with the handle members. The loop is formed from textile tapes 12 arranged in superimposed relation with their longitudinal edges stitched together, as at 13. Tapes or strings 14 are secured to the ends of the loop and in practice are threaded through the eyes 8 and extended rearwardly and attached to the handle members. In order to hold the loop against buckling transversely longitudinally extending inserts 15 are sewed between the tapes 12 at diametrically opposite points of the loop. These inserts are preferably formed from celluloid but any other material possessing the necessary flexibility may be employed.

For the purpose of drawing the loop taut or into gripping engagement with the infant's head, a finger engaging element 16 slidable on the handle member 6 is provided, to which the ends of the tapes or strings 14 are adapted to be attached. The finger engaging element consists of a rectangular body 17 having a dovetail groove 18 in one face which slidably receives the handle member 6, the latter being shaped cross-sectionally, as at 19, from its outer end to a point intermediate its ends to conform to the dovetail recess. 90 Oppositely extending rounded extensions 20, extending at right angles to the handle member 6, project from the opposite ends of the rectangular body.

In the modification disclosed in Figure 6 the handle members are stamped from relatively light and wide gage metal. In this instance a rectangular sleeve 21 provided with a head 22 at one end is received on and attached to the outer end of the handle member 5, and receives the outer end of the other handle member 6 as illustrated. The body 17 of the finger engaging member is slidable on the handle member 5 and is formed with oppositely extending lugs 23 at 105 110

its ends which lie within longitudinal recesses 24 provided in the opposite edges of the handle member 6. It will be observed that the movement of the handle member is limited by the engagement of the lugs 23 with the end walls of the recesses 24.

In use one of the tapes or strings 14 is threaded through the eye of the handle member 5 and extended rearwardly along the handle member and the loop brought rearwardly along the opposite face of the handle member and held against movement, as illustrated in Figure 3. With the loop thus positioned the handle member is inserted to operative position and the other tape or string inserted through the eye of the member 6 which is now inserted into operative position and engaged with the spherical element 9. The loop being now disposed between the arms 7 is engaged around the infant's head either by means of the human hand or a suitable surgical instrument. The strings or tapes are then wrapped about the finger engaging member to secure the loop against displacement. With the knob or spherical element placed against the palm of the operator's hand and the loop tensioned, by exerting manual strain upon the finger engaging element, the device is drawn outwardly.

30. What is claimed is:—

1. In an obstetrical instrument, a pair of separable handle members arranged in opposed relation and having oppositely curved arms at one end, a flexible loop adjustable between the arms and slidably connected therewith, and means associated with the handle members for maintaining tension on the loop.

2. In an obstetrical device, a pair of detachably connected handle members arranged in parallel relation and having their forward ends offset, a flexible human head embracing loop between the offset ends and slidably connected therewith, and a finger engaging element slideable on one of the handle members with which the loop is adapted to be connected whereby the latter may be maintained under tension upon movement of the finger engaging element in an outward direction.

3. In an obstetrical device, a pair of detachably connected handle members arranged in parallel relation and having their forward ends offset, a flexible human head embracing loop between the offset ends and slidably connected therewith, a finger engaging element slideable on one of the handle members with which the loop is adapted to be connected whereby the latter may be maintained under tension upon movement of the finger engaging element in an outward direction, and pliable inserts carried by the loop to prevent the latter from buckling transversely.

4. In an obstetrical device, a pair of paral-

lel handle members, a loop slidably connected with the adjacent ends of the handle members, tapes carried by the ends of the loop, and a tensioning finger grip associated with the handle members and engaged by the tapes to maintain the same under tension.

5. In an obstetrical device, a pair of parallel handle members, a loop slidably connected with the adjacent ends of the handle members, tapes carried by the ends of the loop, and a longitudinally shiftable element to which the tapes are anchored and adapted to be shifted in a rearward direction to tension the loop about the object.

6. In a device of the character described, a pair of detachably connected parallel handle members having curved extensions at their forward ends, a loop formed of flat textile tape adjustable between the extensions and slidably connected therewith, and a tensioning finger grip on one of the handle members and engageable with the ends of the loop to maintain the latter under tension.

7. In a device of the character described, a pair of detachably connected parallel handle members having curved extensions at their forward ends, a loop formed of flat textile tape adjustable between the extensions and slidably connected therewith, a tensioning finger grip on one of the handle members and engageable with the ends of the loop to maintain the latter under tension, and pliable inserts enclosed in the tapes forming the loop to prevent such tapes from buckling transversely.

8. In a device of the character described, a pair of coaxing handle members, a hand engaging member carried by one end of one of the handle members and having a recess to receive the adjacent end of the other handle member, and a textile loop slidably connected with the opposite ends of the handle member, and a tensioning finger grip engageable with the ends of the loop.

9. In a device of the character described, a pair of coaxing handle members, a hand engaging member carried by one end of one of the handle members and having a recess to receive the adjacent end of the other handle member, a textile loop slidably connected with the opposite ends of the handle member, a body having a groove in one face slidably receiving one of the handle members, and oppositely extending finger engaging elements carried by the body to which the ends of the loop are adapted to be attached so that upon movement of the finger engaging elements in a rearward direction the loop will be placed under tension.

Signed at Washington, in the District of Columbia, this 1st day of February, 1928.

EDWIN ODELL.
